HOT TRAY LIFTER

James Demetreon, Kansas City, Mo., assignor to Handi
Caddy Inc., a corporation of Missouri

Filed Nov. 20, 1968, Ser. No. 14,555

Term of patent 14 years

Int. Cl. D8—02

U.S. Cl. D44—4

Fig. 1.

Fig. 2.

Fig. 3.

*Fig. 4.**Fig. 5.**Fig. 6.*

FIG. 1 is a perspective view of a hot tray lifter, showing my new design;

FIG. 2 is a top plan view;

FIG. 3 is a front elevational view;

FIG. 4 is a perspective view of a hot tray lifter, showing another form of my new design;

FIG. 5 is a top plan view; and

FIG. 6 is a front elevational view.

I claim:

The ornamental design for a hot tray lifter, as shown and described.
